UNITED STATES PATENT OFFICE.

FREDERICK E. GROUT, OF ORANGE, MASSACHUSETTS.

AUTOMOBILE.

SPECIFICATION forming part of Letters Patent No. 761,295, dated May 31, 1904.

Application filed December 15, 1902. Serial No. 135,195. (No model.)

To all whom it may concern:

Be it known that I, FREDERICK E. GROUT, a citizen of the United States, and a resident of Orange, in the county of Franklin and State 5 of Massachusetts, have invented certain new and useful Improvements in Automobiles, of which the following is a specification.

This invention relates to improvements in automobiles, and particularly to automobiles 10 which derive their motive power from a steam-engine supplied with steam by a boiler located at the forward end of the vehicle and having a fuel-burning heater for generating steam in the boiler.

15 My present improvements are especially designed for use in connection with a steam-boiler and heater used on the well-known Tonneau type of automobile, although, of course, its application is not limited to this particular 20 type of vehicle.

In automobiles of the Tonneau type it has been found desirable to locate the boiler and heater at the extreme forward end of the vehicle and cover the same by the usual casing 25 or bonnet located at such point, which serves to confine the smoke, gases, and vapor rising from the boiler and heater and to prevent these vapors and gases from blowing directly into the faces of the occupants of the vehicle.

30 It has been found in practice, however, that such a bonnet, while useful and while preventing the direct rise and blowing of these gases and vapors from the top of the boiler into the faces of the persons seated in the rear of the 35 vehicle, does not prevent the rising of these vapors and gases from the bottom of the boiler and heater at a point immediately behind the same, and the result is that in the ordinary type of Tonneau automobile a considerable 40 portion of this smoke, vapor, and gas rises immediately behind the boiler and blows in the faces of the persons seated there, causing them considerable discomfort.

The main object of my present improvements 45 is to provide means for confining all of the escaping steam-vapor and the products of combustion of the heater and leading them to the extreme rear end of the vehicle, where they will be discharged into the open air at a point 50 behind all of the occupants of the vehicle, at

which point they cannot be blown into the faces of persons seated near the rear end of the automobile.

In carrying my invention into effect I make use of a draft or suction apparatus having one or more inlets near the extreme forward end of the vehicle, the suction apparatus being so organized and its inlets so placed that as the vehicle moves forward the natural air-currents will travel through the passages of the apparatus and blow with them all smoke, vapors, and gases and carry the same through the apparatus and discharge these vapors and products of combustion at the rear end of the vehicle, preferably at a point below the floor of 65 the automobile.

An important feature of my improved draft apparatus is its employment not only for the purpose of drawing the steam-vapor and products of combustion away from the forward 70 end of the vehicle, but also for the purpose of supplying to the heater a forced draft, which will force the gases and products of combustion through the openings of the tubular boiler ordinarily employed on automobiles, while at 75 the same time a suction-inlet adjacent to the top of the boiler will draw the vapors and gases away from the top of the boiler and carry them through the draft-tube to the rear end of the vehicle. Thus it will be seen the 80 air-currents set in motion by the forward movement of the vehicle are utilized to force the draft under the heater, and hence to force the products of combustion and heated gases through the boiler, while the suction-inlet 85 above the boiler cooperates to draw such gases and products of combustion away as fast as they are developed by the heating device.

Other features of my invention not hereinbefore referred to will be hereinafter described, and are shown in the accompanying drawings, in which—

Figure 1 is a side elevation of an automobile of the Tonneau type, broken away and in section to illustrate the construction of 95 the draft apparatus. Fig. 2 is a vertical section of the same, the section being taken in line 2 2, Fig. 1, looking in the direction of the arrow. Fig. 3 is a plan of the forward end of the vehicle with the bonnet removed. 100

The automobile shown in the drawings is of the usual Tonneau type, having a long body the floor of which is designated by 2, this body portion being supported, as usual, on 5 springs 3 and 4, secured to the forward and rear axles 5 and 6 of the vehicle, on which axles the wheels 7 and 8 are journaled. At the extreme forward end of the vehicle the heating apparatus, including the boiler, is located and is supported in the ordinary manner and covered by the usual bonnet 10, which serves to give the forward end of the automobile a finished appearance and confines the steam and smoke and gases which escape or 15 are permitted to escape from the boiler and heater. In their general structure these parts of the automobile are or may be substantially the same as in other automobiles of the Tonneau type. The engine to which steam is 20 supplied by the boiler and by which the vehicle is driven is not shown in these drawings, as it constitutes no part of the invention and does not in any way affect the operation of the draft apparatus.

25 The principal feature of my improvements is the employment of a draft-tube which extends from the forward end of the vehicle toward the rear end thereof and has a suction-inlet adjacent to the boiler for the purpose of 30 drawing off and discharging at the rear end of the carriage the smoke, escaping steam, and other products of combustion. This suction-inlet is preferably placed at a point near the top of the boiler, although it may be located in any position suitable for producing a current from the space around the heating apparatus to the draft-tube communicating with the rear end of the carriage. This draft-tube may have at the forward end of the carriage one or more openings communicating directly with the atmosphere and adapted to 40 permit a current of air to travel therethrough and through the draft-tube as the vehicle moves forward. One or more of these openings may be located near the bottom of the vehicle at the forward end of the same and another near the upper forward portion of the carriage, the latter being in the construction shown the principal air-inlet.

45 The particular type of draft apparatus which I prefer to employ is clearly illustrated in Fig. 1, 11 designating generally a draft-tube extending from the upper forward end of the carriage to the lower rear end of the same. 50 This draft-tube may be constructed of any suitable material and may be of any desired cross-section, though I prefer to make use of a tube oblong in cross-section and of considerable cross-sectional area. In the construction 55 shown this draft-tube has a horizontal portion 11' at the upper forward side of the carriage entirely inclosed by the bonnet 10, the draft-tube being then bent downwardly, as at 11", immediately in the rear of the boiler and extending 60 through the floor 2 of the carriage and com-

municating at its lower end with the main portion of the tube 11. At the point 12 a suction-inlet is formed by the forward wall or partition 13 of the draft-tube, this partition lying between the rear upper side of the boiler and the other wall of the tube, and through the suction-inlet 12, formed by this partition, the vapor, smoke, and other waste products will pass downward, as shown by the arrows, after they emerge from the upper ends of the tubes of the 75 boiler 14. It will be noticed that the upper section 11' of the draft-tube is entirely inclosed by the bonnet or cover 10. In order that the bonnet may be removed readily without necessitating the removal of the main portion of the draft-tube, I prefer to provide a detachable tube-section 15, which may be simply slipped into the forward end of the main portion 11' of said tube. This detachable section 15 preferably flares somewhat in order to increase the 80 velocity of the air-current traveling through the draft-tube and also gives the forward end of the carriage a neat appearance. Similar flaring air-inlets will also preferably be employed at the other points at which it is desired to permit the entrance of air into the draft-tube—as, for example, at the point 16 below the heater, at the rear edge thereof. Another inlet, such as 17, may also be placed at the under side of the forward portion of 85 the vehicle, preferably somewhat in advance of the air-inlet 16. The function of this air-inlet 17, however, is not the same as that of the inlet 16 or 15, as instead of communicating directly with the draft-tube 11 the inlet-tube 17 communicates with the under side of the burner placed below the boiler. This burner is designated by 18 and may be of any suitable type. In all cases, however, it should have a multiplicity of burner-openings, so as to heat 90 all portions of the bottom of the boiler, and all of its burner-inlets should be in communication with the inlet-tube 17 in order that a good supply of air may be mixed with the hydrocarbon vapor and in order also that a strong draft may be created in an upward direction through the heater and the boiler. This upward draft not only serves to produce an intense heat under the boiler, but also forces 95 the smoke and other products of combustion 100 through the boiler, and thus facilitates the rapid withdrawal of these vapors and gases from the bonnet by the suction produced at the suction-inlet 12 by the current of air passing through the draft apparatus. The direct currents of air admitted through the inlets 15 and 16 produce a strong suction at the opening 12, and this suction being aided by the force exerted by the air-blast entering the inlet 17 causes all vapors and gases to be rapidly 105 forced through the boiler and then drawn into the inlet 12 and through the draft-tubes 11" and 11 to the rear end of the carriage, where they are discharged at a point where they will 110 not blow in the faces of the occupants of the 115 carriage. The air current passing through the draft-tube 11 will draw off the smoke and other products of combustion from the boiler and the 120 heater, and will draw these products through the draft-tube 11 and the inlet-tube 17 into the burner 18, where they will be burned and the heat 125 generated will be used to heat the boiler. The air current passing through the draft-tube 11 will also draw off the smoke and other products of combustion from the boiler and the 130 heater, and will draw these products through the draft-tube 11 and the inlet-tube 17 into the burner 18, where they will be burned and the heat generated will be used to heat the boiler.

vehicle and cause them discomfort. This draft apparatus therefore serves a double purpose, as it performs not only the function of carrying away escaping steam and products of combustion, but also promotes combustion and favors the rapid production and maintenance of a high steam-pressure in the boiler.

In speeding an automobile or in driving the same at a moderate rate of speed against a strong head-wind the draft through the tubes 11' and 11 may sometimes be excessive unless regulated. For this reason I prefer to place in one of the tubes, preferably in the draft-tube 11", a damper, such as 20, which may be turned more or less to control the draft therethrough. This damper may be operated by a lever or treadle 21, extending through the dashboard 22 in a position to be operated by the driver of the vehicle. With steam-boilers of this type it is customary to employ a hood, such as 25, for confining the products of combustion as they escape from the upper end of the boiler and for protecting adjacent parts of the carriage from the heat of these exhaust-gases, &c. In the present construction the upper portion 11' of the draft-tube is within this hood, but is somewhat narrower than the hood, and openings are left at 26 at opposite sides of this section of the draft-tube, through which a portion of the escaping products of combustion may flow, as indicated by the arrows in Fig. 2. At the upper end of the casing 25 the casing is contracted, as shown at 27, to form a short stack, which passes through a corresponding opening in the top of the bonnet 25 and is closed by a cap or cover 28 when the vehicle is running. When the carriage is brought to a stop, however, as there is no draft or but little draft through the tubes heretofore described, it is desirable to provide an outlet for the smoke, escaping steam, and burned gases, and at such times the cap 28 is raised, as shown in Fig. 2, to permit these products to pass out through the stack 27 instead of at the rear end of the vehicle.

What I claim is—

1. In an automobile, the combination with the body of the vehicle, of a steam-boiler and a heater located at the forward end of said body, a hood for said boiler, and a draft-tube extending from the forward end of said body toward the rear end thereof and having a suction-inlet communicating with said boiler-
hood.

2. In an automobile, the combination with the body of the vehicle, of a steam-boiler and a heater located at the forward end of said body, and a draft-tube extending from the forward end of said body toward the rear end thereof and having a plurality of inlets adjacent respectively to the top and the bottom of the boiler.

3. In an automobile, the combination with

the body of the vehicle, of a steam-boiler and a heater at the forward end of said body, a bonnet covering said boiler, and a draft-tube extending from the forward end of said body toward the rear end thereof and projecting at its forward end through said bonnet and also having a suction-inlet adjacent to the boiler.

4. In an automobile, the combination with the body of the vehicle, of a steam-boiler and a heater located at the forward end of said body, a bonnet covering said boiler, and a draft-tube extending from the forward end of said body toward the rear end thereof and having at its forward end a detachable section projecting through said bonnet, said draft-tube also having a suction-inlet adjacent to the boiler.

5. In an automobile, the combination with the body of the vehicle, of a steam-boiler and a heater at the forward end of said body, a bonnet covering said boiler, a draft-tube extending from the forward end of said body toward the rear end thereof and projecting at its forward end through said bonnet and also having a suction-inlet adjacent to the boiler, a damper in said draft-tube, and a damper-operating device extending through said draft-tube and bonnet.

6. In an automobile, the combination with the body of the vehicle, of a steam-boiler and a heater located at the forward end of said body, and a draft-tube extending from the forward end of said body toward the rear end thereof and having at its forward end a pair of air-inlets one of which communicates directly with the interior of said tube and the other of which communicates through the boiler with the interior of the draft-tube, said draft-tube also having a suction-inlet adjacent to the boiler.

7. In an automobile, the combination with the body of the vehicle, of a steam-boiler and a heater located at the forward end of said body, a bonnet covering and surrounding said boiler, a hood constituting an extension of said boiler and having at its upper end an outlet, a cover for said outlet, and a draft-tube extending from the forward end of said body toward the rear end thereof and having a suction-inlet adjacent to the boiler and passing through and of less width than said hood.

8. In an automobile, the combination with the body of the vehicle, of a steam-boiler and a heater located at the forward end of said body, a bonnet covering said boiler, a hood for said boiler, and a draft-tube extending from the forward end of said body toward the rear end thereof and through both the said bonnet and the said hood and having a suction-inlet communicating with the hood.

9. In an automobile, the combination with the body of the vehicle, of a steam-boiler and a heater located at the forward end of said

body, a hood for said boiler, and a draft-tube extending from the forward end of said body toward the rear end thereof and having a plurality of inlets adjacent respectively to the top and the bottom of the boiler and also having a suction-inlet communicating with the boiler-hood.

Signed at Orange, in the county of Franklin and State of Massachusetts, this 9th day of December, A. D. 1902.

FREDERICK E. GROUT.
